DESIGN FOR A COMBINATION SMOKER'S AND READER'S STAND

Irvin Kain, Columbus, Ohio

Application June 22, 1938, Serial No. 77,996

Term of patent 3½ years

To all whom it may concern:

Be it known that I, Irvin Kain, a citizen of the United States, residing at Columbus, in the county of Franklin and State of Ohio, have invented a new, original, and ornamental Design for a Combination Smoker's and Reader's Stand, of which the following is a specification, reference being had to the accompanying drawing, forming part thereof.

smoker's and reader's stand, showing my new design.

I claim:

The ornamental design for a combination smoker's and reader's stand, as shown.

IRVIN KAIN.
